UNITED STATES PATENT OFFICE.

ULRICH E. ROHDE, OF ROCK RAPIDS, IOWA.

SANITARY-CLOTH-TOWEL MACHINE.

1,070,737.

Specification of Letters Patent. Patented Aug. 19, 1913.

Application filed May 11, 1911. Serial No. 626,542.

To all whom it may concern:

Be it known that I, ULRICH E. ROHDE, a citizen of the United States, residing at Rock Rapids, in the county of Lyon and State of Iowa, have invented certain new and useful Improvements in Sanitary-Cloth-Towel Machines, of which the following is a specification, reference being had to the accompanying drawings.

10 This invention relates to improvements in machines for furnishing towels and the like; and an object of this invention is to provide a machine of this character which will be adapted and designed for either 15 vending the towel as a commodity or for supplying a towel for merely a single and immediate use.

Another object of this invention is to provide a towel-supplying machine which will 20 be simple in construction, comparatively cheap in manufacture and most efficient, secure and reliable in use.

A third object of this invention is the provision in a machine of this character of 25 suitable carrier-devices by which the towels are moved to the delivery opening.

A fourth feature of this invention is the provision in a machine of this character of mechanism for withdrawing the soiled 30 towels from the delivery opening and disengaging the same from the feed-mechanism.

A further object of this invention is the provision in a machine of this character of 35 mechanism for controlling the delivery opening from the feed mechanism.

A sixth object of this invention is the provision in a machine of this character of mechanism by which tampering with the 40 slide which covers the delivery opening in an endeavor to open surreptitiously the same will result in locking the feed mechanism.

Other features of this invention will be set forth in the description and claims which 45 hereinafter follow.

In the drawings illustrating the principle of this invention and the best mode now known to me of applying that principle, Figure 1 is a front elevation of my new 50 towel-supplying machine; Fig. 2 is a section on the line A—A of Fig. 1; Fig. 3 is a detail sectional view showing the feed mechanism in the position assumed by it when a towel is presented to the delivery 55 opening; Fig. 4 is a section on the line B—B of Fig. 3, Fig. 5 is a detail in central

vertical section of a towel-holding clip; Fig. 6 is a detail showing in front elevation the carrier-part of the clip shown in Fig. 5; Fig. 7 is a perspective view of the clasp part 60 of the clip shown in Fig. 5; Fig. 8 is a perspective view showing another form of clip; Fig. 9 is a perspective view showing a towel-containing package, where the towel is to be sold; Fig. 10 is a detail showing 65 the coin-controlled mechanism in central vertical section, the operating plunger and slide-rod actuated thereby; Fig. 11 is a detail showing the slide-rod viewed in the direction of the arrow X of Fig. 10; Fig. 12 70 is a section on the line C—C of Fig. 10; Fig. 13 is a section on the line D—D of Fig. 10; and Fig. 14 is an end view of the coin-controlled mechanism looking in the direction of the arrow Y in Fig. 10, the casing 75 being shown removed.

Nearly all the mechanism for supplying or feeding the towel is inclosed within a cabinet *a* the back of which is fastened to a suitable wall-support *b* and the front of 80 which is formed with an opening *c* which is controlled by a slide *d*. The upper end of a hollow pedestal *e* extends up into the cabinet *a* and within this hollow pedestal is slidably fitted a plunger *f* the upper end 85 of which carries a pair of leaf-springs *g*. The free ends of the latter are provided with inwardly-projecting lugs *h*. Near the bottom of the wall support *b* there is fastened a bracket *i* in which is fulcrumed the 90 rear end of a pedal lever *j* the outer free end of which is provided with a foot-rest *k*. This pedal lever *j* is formed with a slot *j'* and the pedestal *e* is formed with slots *e'*; and through these slots *j'*, *e'* extends a 95 headed pin *m*, which passes also through the plunger *f*. The lower end of a coil spring *n* is fastened to the pedal lever *j*, while its upper end is fastened to the bottom of the cabinet. By placing his foot on the 100 foot-rest *k*, the outer end of the pedal lever *j* may be depressed by the operator against the tension of the coil spring *n*; and this downward movement of the pedal lever *j* will be transmitted through the pin *m* to 105 the plunger *f*, whereby the latter will be moved downwardly.

Inside of the cabinet and near the top of its front wall there is fastened a suitable shaft hanger *o* in which is mounted a fixed 110 shaft *p*; and on the latter there is mounted idly or loosely a grooved pulley *q* over which

passes a wire cord *r*, the upper end of which is fastened to the top of a slide-rod *s* mounted in the upper end of the pedestal *e*. The lower end of the slide rod *s* is reduced and 5 is provided with shoulders *t* with which are adapted to engage or interlock the lugs *h* on the leaf-springs *g*. Rotatably mounted in suitable journal bearings *u* fastened to the sides of the cabinet are the ends of a trans- 10 verse rock-shaft *v* fast upon which is mounted a grooved pulley *w* around which is wound and to which is fastened the other or lower end of the wire cord *r*. Upon this same transverse shaft *v* there is fastened a 15 feed-disk *x*. Within the cabinet there is mounted a hanger *y* the upper end of which is fastened to the top of the cabinet and in the lower end of which is pivoted the rear ends of the levers *z* the other or front ends 20 of which are attached to the top of a U-shaped yoke or link 2 the lower or base end of which is pivotally fastened to the upper end of the slide *d* which controls the opening *c*, through which access to the tow- 25 els is had. About midway of the levers *z* there are pivotally fastened thereto the upper ends of a pair of links 3 the lower curved ends of which are pivotally connected with the feed-disk *x*. To the latter is also fastened the lower end of a coil-spring 4 the 30 upper end of which is fastened to the back of the cabinet. To the back of the cabinet there is also fastened a guide-bracket 5 in which is adjustably fitted the upper end of 35 an inclined guide-bar 6 the lower end 6' of which partially encircles the feed-disk *x* and is provided with spring fingers 7 which lie on opposite sides of the feed-disk *x*. To the front wall of the cabinet and within the 40 same there is fastened the upper end of an inclined bar 8 the lower end 8' of which is curved and partially encircles the feed-disk *x*. The opposed lower ends 6', 8' of the bars 6, 8 closely approach each other and 45 together substantially encircle the lower half of the feed-disk *x*. The fingers 7 lie above and extend forwardly over the lower end 8' of the arm or bar 8. Extending laterally from the latter is a lug 9 and projecting 50 from the periphery of the feed-disk *x* is a stop 10. The lug 9 and stop 10 limit the rotation of the feed-disk *x* in one direction. Each towel 11 is provided with a clip or fastener 12 through the loop of which passes 55 the guide bar 6, downwardly upon which the clip 12 slides by gravity. In the rim or peripheral face of the feed-disk *x* is formed a transverse groove *x'* which is shaped to receive the horizontal top portion 12' of the 60 clip 12. If now the rock-shaft *v* be turned (as by pulling down the slide-rod *s* and the attached end of the wire-cord *r*), thereby rotating the feed-disk *x* against the tension of the spring 4, a clip 12 carrying a towel 11 65 will be carried toward the opening *c*, the

top 12' of the clip traveling over the lower end 6' and the spring fingers 7 and the lower end 8' of the bar 8 which enters the loop of the clip. The same rotary motion of the feed-disk *x* will lower the arms 3 and will thereby pull down the levers *z*, which through the link 2 will force downwardly the slide *d* and permit access to be obtained to the towel presented at the opening *c*. When the coil spring 4 is allowed to contract, it will retract and rotate in the opposite direction the feed-disk *x* and the latter will now carry the clip 12 backwardly along the lower portion 8' of the curved bar 8. The horizontal portion 12' of the clip 80 will pass under the forwardly-extending fingers 7, which will cause the disengagement of the clip from the feed-disk. The towel will now fall by gravity into the chute 13 and down the inclined bottom of the same 85 into the bottom of the cabinet. At the same time the link-arms 3 are forced upwardly and swing in the same direction the free front ends of the levers *z*, which through the link-rod 2 pulls upwardly into its closing 90 position the slide *d*.

In order to clutch the upper end of the plunger *f* to the lower end of the slide-rod *s*, the following mechanism is provided: Fasted at its inner end to the pedestal *e* 95 is a casing 14 which extends forwardly from and outside of the front wall of the cabinet. The top of the casing 14 is formed with a keyhole-shaped slot 15 and with a pair of slots 16 through each of which upwardly projects a stud 17 formed upon the outer front end of a finger 18 pivoted on a pin 18'. Between the inner ends of the fingers 18 lie the leaf-springs *g* which carry the lugs *h*. Each finger 18 is further formed 105 with an upwardly-extending lug 19 to which is attached one end of a contractile coil-spring 20.

The operation of the machine herein described is preferably coin-controlled; and in 110 order to make operative the towel-feeding mechanism through the medium of the pedal-lever *j* and the plunger *f*, a coin 21 is placed in the enlarged portion 15' of the keyhole-shaped slot 15. Projecting upwardly through the narrow portion 15'' of the latter is a stem 22 having at its upper end a finger-piece 23. To the stem 22 is attached a slide 24, which is recessed to receive a part of the coin 21. When the finger-piece 23 is forced toward the front wall of the cabinet, the slide 24 pushes the coin 21 in the same direction and the latter, acting as a cam, spreads the front or outer ends or jaws of the pivoted fingers 18 apart, whereby the inner ends or jaws of the latter are forced toward each other so as to press the leaf-springs *g* toward the lower end of the slide-rod *s* and thereby to carry the lugs *h* 125 into interlocking relation with the shoulders 130

t of the slide-rod. It is obvious that, if the 5 pedal-lever *j* be swung downwardly by pressing upon the foot-rest *k*, the slide-rod *s* will now be pulled downwardly and the rock-shaft *v* will be turned, as hereinbefore described.

To release the coin 21 the following 10 mechanism is provided: Pivoted on the studs 18' with the fingers 18 and underneath the same is a pair of fingers 25 upon the front 15 ends of which the coin 21 slides as it is pushed forward by the plate 24. Attached to the slide-rod *s* is a fork 26; and when the slide-rod *s* is pulled downwardly by the plunger *f*, as hereinbefore described, the 20 fork 26 straddles and presses toward each other the inner ends of the pivoted fingers 25, thereby throwing from each other the outer ends of these fingers which are recessed and curved sufficiently to permit the 25 penny or coin to drop between them, when they are thus thrown apart. When the fork 26 moves upwardly, as the slide-rod *s* resumes its initial position, the contractile coil 30 springs 20, and the leaf spring 27 restore the fingers 18, 25, respectively, to their initial position.

If the towel 11 is not to be sold but is merely to be furnished for use, it may be 35 formed with an eyelet 28 through which is passed the pointed or V-shaped end 12" of the wire clip 12, the towel being drawn or knotted between the sides forming the V-shaped end of the clip, as is clearly shown in Fig. 8. A different form of clip is shown 40 in Figs. 5, 6 and 7 where the legs 29 of the clip 30 are connected by a plate 31 the upper edge 32 of which is serrated. The edge of the towel is passed over this serrated edge 32 45 and a U-shaped clasp 33 is then passed over the edge of the towel, thereby fastening the same securely in the clip. Inspection of Figs. 5 and 6 will show that any pull upon the free or hanging part of the towel will result in engaging the towel all the more 50 firmly with the clip.

When the towel is sold, it is placed, carefully folded, in a sealed bag 34 of paper or other suitable material, and the bag is fastened to a clip 30. The customer merely tears the paper bag from the clip and the latter is withdrawn within the cabinet by the return movement of the feed-disk *x*.

When the link arms 3 are in the normal 55 or raised position, as shown in Fig. 2 their curved lower ends lie or project forwardly beyond the axial line of the transverse shaft *v*. When the slide *d* is in its closed position, it will be found impossible to open the slide *d*, except by operating the coin-controlled 60 mechanism as hereinbefore described; for, if it be attempted to force the slide *d* downwardly into open position except through the medium of the feed-disk *x* and its connected mechanism in the normal manner, the

engagement of the stop 10 with the lug 9 will effectually prevent this since the tendency is to throw the lower ends of the link-arms 3 to the front; and even if one of these parts 9, 10 were omitted, the lower ends of the link-arms 3, being positioned as just described, will be thrown to the front into a position in which further movement of the lever *z* and the link-arms is impossible without breaking the mechanism. The opening *c* is made so narrow that it will be impossible to attempt successfully, after the slide *d* has been opened, to grasp the clean towels which hang from the guide-bar 6. The bottom of the chute will prevent access to the soiled towels, when the slide *d* is open.

I claim:

1. A towel-delivering machine comprising a casing formed with a suitable delivery-opening; guiding means for guiding the towel to said opening; and oscillating feed-mechanism which first moves the towel along said guiding means to said opening and then swings back to its initial position and withdraws the towel from the opening; said guiding means being formed with a towel-releasing device which disengages the towel from said feed-mechanism during the movement of the same from said opening to its initial position.

2. A towel-delivering machine comprising a casing formed with a suitable delivery-opening; a guide-bar for guiding the towel to said opening; and oscillating feed-mechanism which first moves the towel along said guide-bar to said opening and then swings back to its initial position and withdraws the towel from the opening; said guide-bar being formed with a finger which engages the towel from said feed-mechanism during the movement of the same from said opening to its initial position.

3. A towel-delivering machine having a casing formed with a suitable delivery-opening; guiding means for guiding the towel to said opening; a rock-shaft; a wheel-like oscillating towel-feed device mounted upon said rock-shaft; mechanism which rocks said shaft and oscillates said towel-feed device to move the towel first along said guiding means to said opening and then away from the latter as said towel-feed device swings back to its initial position; said guiding means being formed with a towel releasing device which disengages the towel from said towel-feed device during the movement of the same from said opening to its initial position.

4. A towel-delivering machine comprising a casing formed with a suitable delivery-opening; guiding means for guiding the towel to said opening; oscillating feed mechanism which first moves the towel along said guiding means to said opening and then

70

75

80

85

swings back to its initial position and withdraws the towel from the opening; said guiding means being formed with a towel-releasing device which disengages the towel 5 from said feed-mechanism during the movement of the same from said opening to its initial position; and a shutter which controls said delivery-opening and which is operatively connected with said feed-mechanism; said shutter being moved to an open position by said feed-mechanism when the same moves toward said opening and being restored to closing position by said feed-mechanism when the latter swings back to 15 its initial position.

5. A machine of the character described having a casing formed with a delivery opening; clips to which the towels are fastened; guiding means for said clips; a feed-disk which engages said clips; mechanism for moving said feed-disk toward and from said opening to feed said clips; and means for disengaging the clips from said feed-disk.

25 6. A machine of the character described having a casing formed with a delivery opening; clips to which the towels are fastened; guide-bars; a feed-disk which moves said clips along said guide-bars toward and 30 from said opening; mechanism for rocking said feed-disk to feed said clips; and means for disengaging said clips from said feed-disk.

7. A machine of the character described 35 having a casing formed with a delivery opening; clips to which the towels are fastened; guide-bars; a feed-disk for moving said clips toward and from said opening along said guide-bars; means for disengaging said clips from the latter and said feed disk; and means for controlling said opening.

40 8. A machine of the character described having a casing formed with a delivery

opening; clips to which the towels are fastened; guide-bars; a rock shaft; a feed-disk 45 mounted upon said rock shaft and arranged to engage said clips and feed the same toward and from the said opening; means for rocking said rock shaft; and means for disengaging the clips from said feed-disk. 50

9. A machine of the character described having an operating mechanism provided with fingers; carrier devices for holding the towels; feed mechanism for moving said carrier devices; and means for clutching the 55 fingers of said operating mechanism to said feed mechanism.

10. A machine of the character described having an operating mechanism provided with fingers; carrier devices for holding the 60 towels; feed mechanism for moving said carrier devices to feed the towels; and means for clutching and unclutching the fingers of said operating mechanism to and from said feed mechanism. 65

11. A machine of the character described having a casing formed with a delivery opening; an operating mechanism; carrier devices for holding the towels; mechanism for controlling said opening; mechanism for moving the last-named mechanism from closed to open position and from open to closed position and said carrier devices toward and from said opening; and means for clutching and unclutching said operating mechanism to and from said feed mechanism. 70 75

In testimony whereof I hereunto set my hand at Rock Rapids, Iowa, this 8th day of May, A. D., 1911, in the presence of the two 80 undersigned witnesses.

ULRICH E. ROHDE.
